UNITED STATES PATENT OFFICE.

JAMES W. DUFFEE AND CHARLES WESTON, OF WASHINGTON COURT-HOUSE,
OHIO.

STATION-INDICATOR.

SPECIFICATION forming part of Letters Patent No. 365,736, dated June 28, 1887.

Application filed February 18, 1887. Serial No. 228,075. (No model.)

To all whom it may concern:

Be it known that we, JAMES W. DUFFEE and CHARLES WESTON, of Washington Court-House, in the county of Fayette and State of Ohio, have invented a new and Improved 5 Station-Indicator, of which the following is a full, clear, and exact description.

Our invention relates to devices to be carried on railway-cars for indicating the names 10 of stations and their distances apart, and has for its object to provide a simple, inexpensive, and efficient indicator of this class which is specially adapted to be placed in every car of a train, and to allow all the indicators on the 15 train to be connected for simultaneous operation by compressed air or other fluid under control of the engineer or operator.

The invention will first be described, and then pointed out in the claims.

20 Reference is to be had to the accompanying drawings, forming a part of this specification, in which similar letters of reference indicate corresponding parts in all the figures.

Figure 1 is a front view of our improved station-indicator. Fig. 2 is a vertical transverse sectional elevation taken on the line xx , Fig. 1. Fig. 3 is a transverse section taken on the line yy , Fig. 1. Fig. 4 is a partial longitudinal vertical sectional elevation taken on the line zz , Fig. 2. Fig. 5 is a diagram view illustrating the application of the indicators to a railway-train and the connections for operating them from a compressed-air reservoir on the engine, and Fig. 6 illustrates the application 35 of an indicator to a street-railway car.

The case or box A of the indicator may have any desired size and will be made with a hinged front, a , having a glass panel, a' , through which the names of the stations or stopping-places of 40 the car, and their distances apart, produced on the canvas-band B, may be seen. This band B is attached at opposite ends to two rollers, C D, on one of which the band is wound, to be unwound from it onto the other roller, 45 and the band passes over rollers E E, which guide it quite closely to the front of the case. (See Fig. 3 of the drawings.) The rollers C D have end flanges, $c d$, respectively, to guide the canvas band as it unwinds from or winds on 50 them. The ends of the rollers are preferably fitted with metal cap-plates, those at one end

of the rollers having studs which are journaled in suitable bearing-plates held to the case, and the plates at the other end having sockets in which bearing-pins enter, as shown in Fig. 4, 55 55 the bearing-pin F of the roller D being fast to the roller and journaled in the end of the case, so that a crank, G, may be applied to the end f of the pin which projects through the case, for turning back the canvas or rewinding it 60 onto the roller D from the roller C, as presently explained. A brake-rod, H, held in the case A, bears on the periphery of the end cap-plate, d' , of the roller D to prevent turning of the rollers and the band B, except as they are 65 turned by operating mechanism provided for that purpose.

At one end of the indicator-case A there is fastened a cylinder or barrel, I, in which is placed a rod, J, having at its lower end a 70 packed piston, K, which fits the cylinder I and is adapted to fall upon a noise-deadening packing, k , fitted on a cap, L, screwed to the lower end of the cylinder, and having a hole, l , for the passage of compressed air to the cylinder from a pipe, M, which will be connected with a reservoir containing the air or other fluid under pressure. A cap, L' , fitted to the 75 upper end of the cylinder I, contains a noise-deadening packing, k' , against which a shoulder on the piston-rod J strikes to limit the upward movement of the piston. The cylinder I has a side slot, i , for passage of a series of tappets or arms held to the piston-rod, as 80 next described.

A tappet, N, is pivoted to the piston-rod J, and when down to normal position projects to engage one of a series of pins, n , fixed to the end bearing-plate, c' , on the roller C, for turning the roller one-quarter around as the piston-rod is raised, and a tappet, O, fixed to the rod J below the one N, has a shoulder-notch, o , which acts as a stop to the roller C by engaging the pin n next following the pin acted on by the tappet N, and a tappet, P, fixed to the 90 rod J, has a notch which locks with the pin acted on by the tappet N when the piston-rod falls, and as shown in Fig. 2 of the drawings. A tappet, R, pivoted to the rod J, acts, when the rod rises, to turn a cranked arm or part, s , 95 of a bent wire, S, which is journaled in a suitable support, T, held to the case A, and car-

ries a tongue or clapper, *u*, which strikes a bell, *U*, held to the case, every time the piston-rod is raised, and thus serves as a signal to attract the attention of the passengers to the indicator for noticing the movement of the band *B* in the case, or rather the name of the next station or stopping-place displayed on the band. An elastic arm, *w*, held to the case *A*, and against which the wire *S* strikes, prevents a second contact of the tongue with the bell. The tappets *N R* are free to turn past the respective parts *n s* which they operate as the piston-rod falls.

A bent lever, *V*, which is fulcrumed at *v*' to the case *A*, projects inward beneath the roller-locking tappet *P*, and whereby when the outer end, *v*, of the lever is lowered the tappet *P*, and with it the piston-rod *J*, will be lifted far enough to allow the pins *n* on the roller *C* to 20 rotate clear of the tappet while the crank *G* is turned to wind the band *B* back onto the roller *D* from the roller *C* at the end of the journey.

By reference to Fig. 5 of the drawings it will be seen that we purpose placing an indicator at each end of each car of a train, and connect the pipes *M*, leading from all the indicators to coupled pipes *W*, under the cars, and these pipes *W* will be connected to a reservoir, *X*, on the locomotive engine or tender, from which the compressed air or other fluid will be taken to operate all the indicators of a train simultaneously at the will of the engineer, who opens a valve at the reservoir, admitting 35 the fluid to the pipes.

It is obvious that as the fluid enters the cylinder *I* of each indicator the pressure of it on the piston *K* will raise it to operate the rod *J* for turning the band *B*, as above described, 40 and an exhaust-hole, *i'*, is provided in each cylinder *I*, through which the fluid may escape after the rod *J* is fully lifted and until the engineer closes the valve at the reservoir, which he will do promptly to avoid waste of the fluid.

Our invention may also be applied to street-railway cars, as illustrated in Fig. 6, the pipe *M* then being substituted by a rod, *M'*, which passes or may pass below the car-floor and be connected with one end of a lever, *Y*, fulcrumed 50 to the car-platform and having a treadle-bar, *Z*, which will be depressed by the driver for operating the rod *J* to turn the rollers and band to display the names of the successive streets or stopping-places at the face of the indicator 55 inside the car for convenience of the passengers, as will readily be understood.

Having thus described our invention, what we claim as new, and desire to secure by Letters Patent, is—

1. A station-indicator constructed with rollers, a band carrying the names of the stations and adapted to wind on the rollers, a cylinder, a piston-rod and piston fitted therein, mechanism connecting the rod with one of the band-rollers for turning it and the band when the rod is moved endwise, and a pipe connected to

the cylinder to convey fluid under pressure for operating the piston-rod, substantially as shown and described.

2. A station-indicator constructed with rollers, a band carrying the names of the stations and adapted to wind on the rollers, a cylinder, a piston-rod and piston fitted therein, tappets on the rod, and studs connected to one of the band-rollers and with which the rod-tappets engage for turning the rollers and band, and a pipe connected to the cylinder to convey fluid under pressure for operating the piston-rod, substantially as shown and described.

3. The combination, in a station-indicator, 80 of a case, *A*, rollers *C D*, journaled therein, a band, *B*, carrying the names of the stations and connected to the rollers, a cylinder, *I*, in the case, a piston-rod and piston, *J K*, in the cylinder, pins *n* on one of the rollers, a tappet, *N*, pivoted to the rod *J* and adapted to engage the pins *n*, and stop-tappets *O P* on the rod *J*, and adapted to engage the roller-pins *n*, substantially as shown and described.

4. In a station-indicator, the combination, 90 with a band wound on rollers, one of which is provided with a shaft to receive a crank, a cylinder or guide, *I*, and a rod, *J*, carrying a tappet, *P*, adapted to lock onto pins on one of the rollers, substantially as specified, of a lever, *V*, arranged below the tappet *P* and extending outside the indicator-case, substantially as shown and described, whereby when said lever is operated the band-rollers will be unlocked to allow rewinding of the band, as 95 set forth.

5. In a station-indicator, the combination, with a case supporting rollers and a band thereon carrying the names of the stations, of a cylinder, *I*, in the case, and provided with 105 a piston-rod and piston adapted to actuate the rollers, substantially as specified, and a pipe-connection, as *M*, admitting fluid under pressure to the cylinder, and said cylinder having an exhaust-opening, *i'*, substantially as shown 110 and described.

6. In a station-indicator, the combination, with rollers, a band thereon carrying the names of the stations, and a rod, as *J*, carrying mechanism adapted to turn the rollers and band, substantially as specified, of a tappet, *R*, on the rod, a bell-clapper rod, *S*, having an arm, *s*, in the path of the tappet, and a bell, *U*, which the clapper strikes as the rod *J* is moved endwise, substantially as shown and 120 described.

7. The combination, in a system of station-indicators for railway-trains, of one or more indicators in each car of a train, each indicator having a cylinder and a piston adapted 125 to actuate mechanism for operating the indicator to display the names of the successive stations, pipes connected to the indicator-cylinders, and pipes below the cars connected to the cylinder-pipes and adapted to be coupled, 130 and a compressed-fluid reservoir carried on the engine or train and connected to the

coupled pipes to operate all the indicators of the train simultaneously, substantially as shown and described.

8. The combination, with a railway-car, of an indicator made with rollers and a band thereon carrying the names of the stations, and a cylinder or guide carrying a rod adapted when moved endwise to turn the rollers or band, substantially as specified, a rod, M',

connected to the roller-operating rod, a lever, Y, connected to the rod M', and a treadle-bar, Z, on the lever, substantially as shown and described.
